SECTIONAL BOAT

Joe H. Jenkins, Henning, Tenn.

Application July 8, 1947, Serial No. 759,529

18 Claims. (Cl. 9—2)

1

This invention relates to sectional boats.

An important object in the invention is to provide a novel boat construction formed of a number of sections which are separable to facilitate transportation of the boat and which are readily capable of assembly into a rigid unit forming a boat of any desired shape.

A further object is to provide such a boat construction wherein novel leak-preventing means is provided between all of the separable sections, thus rendering the boat completely water-tight when in use.

A further object is to provide novel means for effectively locking the several sections in proper positions relative to each other.

A further object is to provide novel deformable leak-preventing means between the several boat-sections together with means for latching the sections in proper relative positions, and to provide novel manually operable means for bringing the sections into tightly clamped relation for the latching operation and to properly effect the deforming of the leak-preventing means so that the latching means will hold the leak-preventing means under substantial pressure to prevent leakage.

Other objects and advantages of the invention will become apparent during the course of the following description.

In the drawings I have shown one embodiment of the invention. In this showing:

Figure 1 is a side elevation of a complete boat of canoe shape constructed in accordance with the invention,

Figure 2 is a plan view of the same,

Figure 3 is an enlarged detailed fragmentary sectional view on line 3—3 of Figure 2,

Figure 4 is a sectional view, still further enlarged, taken substantially on line 4—4 of Figure 3,

Figure 5 is a fragmentary detailed perspective view of one of the latches and its associated operating means, the parts being shown separated from their normal positions,

Figure 6 is an inside face view of one of the bow sections of the boat and a portion of one of the next adjacent sections, shown separated,

Figure 7 is a fragmentary perspective view of several associated boat sections, shown somewhat separated,

Figure 8 is a section on an enlarged scale taken substantially on line 8—8 of Figure 6 showing the position of the parts assembled,

Figure 9 is a similar view on line 9—9 of Figure 2, and,

Figure 10 is a detailed perspective view of a

2

substitute stern section or transom used when an outboard motor is to be employed with the structure.

Referring to the drawings, the numeral 10 designates the boat as a whole shown in Figures 1 and 2 as being the canoe type and having duplicated bow sections 11 each of which is made up of two half-sections 12 to be referred to more in detail later. The body of the boat is made of a plurality of sections 13 which are substantial duplicates of each other and vary only in that the sections adjacent the bow sections are slightly curved so that the outer surfaces of these two sections will be flush, as indicated in Figures 1 and 2. Each of the body sections is formed of a pair of half sections 14.

If desired, the boat may be provided with buoyancy-increasing pontoons which also tend to minimize the danger of capsizing. In the present instance, the pontoons have been illustrated as elongated elements 17 (Figures 1, 2 and 7) of any desired internal construction and each provided on its inner face with spring clips 18 engageable in preferably sheet metal sockets 19 secured to the outer surfaces of the sections 13 adjacent the top thereof. The pontoons 17 of the sections 13 adjacent the bow sections may be curved inwardly as in Figure 2 and upwardly toward their extremities as in Figure 1.

Except as specifically referred to below, the same means is preferably employed for securing the various sections and half-sections to each other. Referring to Figures 3 and 4, it will be noted that the hull portions of the sections and half-sections are preferably formed of sheet metal, and the body portion of each section is flush with that of the next adjacent section in each instance, as clearly shown in detail in Figure 4. The metal forming the hull portions of this section is extended upwardly to form relatively deep flanges 22 and 23. These flanges are substantially identical except that one of them, for example, the flange 22, is bent to provide a socket 24 having tapered sides 25 for engagement

with the corresponding faces of a deformable packing member 26 the opposite edge of which is seated in and secured to a socket 27 formed in the other flange, for example the flange 23. One of the deformable packing members 26 is arranged

between the adjacent contacting portions of each section and half-section to form a leak-proof joint as further described below.

The flanges 22 and 23 extend upwardly to an extent greatly enlarged in Figure 4 and terminating at their upper edges in out-turned flanges 28 each of which is welded or otherwise secured to

a casing section 29 which curves outwardly and downwardly in Figure 4 and then outwardly to be welded at its extremity to a strip 30 similarly or otherwise suitably fixed to the hull portion of the corresponding boat section. The casing sections 29 combine to form housing means for a mechanism to be referred to later. These casing sections are shown approximately in their true proportions in Figure 7, and while these casing sections have been specifically defined with respect to the joint occurring in the plane of separation in opposite sides of the boat, similar casing sections are formed with respect to all of the abutting joints of all of the boat sections as will become more apparent below.

One of the flanges in Figure 4, for example the flange 22, is provided with a bracket 34 welded to the flange and provided with a preferably integral socket 35 in which is slidably arranged to the adjacent end of a latch bolt 36 slightly spaced from the head 37 of the socket 35 when the parts are assembled. The latch bolt 36 carries a shank 38 having its outer end threaded in a nut 39, and a compression spring 40 is arranged between the head 37 and nut 39 to urge the bolt 36 toward the right as viewed in Figure 4.

The other flange, namely the flange 23, is provided with a bracket 44 having outstanding arms 45 forming bearings for a shaft 46 the operation of which will be described below. The bracket 44 further includes a socket 48 in which the projecting end of the bolt 36 extends. It is preferred that the members 35 and 48 be out-of-round, for example elliptical with the bolt 36 similarly shaped, as shown in Figure 3. This is for the purpose of preventing rotation of the bolt 36 for a reason which will become apparent.

The shaft 46 carries a crank finger 50 engageable with the straight end wall of a notch 51 formed in the bolt 36. Rotation of the shaft 46, as further described below, tends to force the bolt 36 to a latch position.

The bolt 36 is further provided with a latching notch 52 engageable by one arm 53 of a bell crank lever 54 the other end of which is preferably twisted as at 55 (Figure 3) for a purpose to be described. The bell crank lever 54 is pivoted as at 56 to an arm 57 preferably formed integral with the socket 48.

The socket 48 is provided with an upstanding bracket 60 in the vertical plane of the latch 36. A compression spring 61 is arranged between the upper end of the bracket 60 and the lever arm 53 to urge the latter downwardly. Obviously, the socket 48 is apertured for the extension therethrough of the crank 50 and arm 53. The aperture 62 for the crank 50 is elongated to permit reasonable swinging movement thereof about the axis of the shaft 46. The aperture 63 for the lever arm 53 relatively snugly fits such arm to prevent lateral movement thereof, that is, movement longitudinally of the bolt 36.

One of the complete operating units shown in Figure 4 has been described above, and it will be apparent that any number of these units will be employed as determined by the length of the separable body sections. For example, in the sections shown in Figures 1 and 2, it usually will be found advisable to employ three operating units for each transverse section of the boat, two such units being shown in Figure 3. As shown in Figure 3, the housing defined by the casing members 29 is provided with an end wall 68 carrying bearings 69 in which the shaft 46 is rotatable. This shaft carries an operating crank 70 projecting

through a suitable slot 71 in the corresponding casing section 29, this slot obviously being elongated in a plane perpendicular to the axis of the shaft 46. Accordingly the handle 70 is adapted to be swung to rock the shaft 46 for its intended purpose described below.

Along the longitudinal axis of the boat the hull portions are bent upwardly to form the flanges 22 and 23, previously described. The hull portions at the ends of the sections are similarly bent upwardly, and thus are formed the walls 68 forming the ends of the housing as described above in Figure 3. Connected to such flanges or walls 68 are casing sections 75 shown in elevation in Figure 3 and identical in cross section with the casing sections 29. The only difference between these elements is the fact that the casing sections 29 are straight from end to end (Figures 7 and 8) while the walls 68 and casing sections 75 follow the transverse contour of the boat as shown in the same figures.

The casing sections 75 house the same operating mechanism as that described above and shown in Figures 3 and 4 except that in place of the rigid shaft 46 for rocking the crank fingers 50, a flexible shaft 76 is employed for each boat section 14. However, the shaft 76 is operated in the same manner as the shaft 46 by one of the cranks 70.

The mechanism shown in Figures 3 and 4 is applicable as described for each of the boat sections 14. For the bow sections 12, casing sections 80 are formed with their inner ends in alignment with the casing sections 29 and curve upwardly and inwardly to follow the bow contour as shown in Figures 6 and 9. Similarly, flanges 81, corresponding to the flanges 22 and 23, are formed on the hull portions of the bow sections 12 and follow the contour of the casing sections 80. The mechanism for securing the half-sections of each bow section 12 to each other are identical with the mechanism shown in Figures 3 and 4 except that a flexible shaft 82, similar to the shaft 76, is employed for rocking the crank fingers 50 of the operating mechanism.

In conjunction with the various mechanisms described for clamping the sections together and as shown in detail in Figures 3 and 4, it will be noted that the twisted ends 55 of all of the bell crank levers are engaged by flexible elements 83, this type of operating element for the sets of bell crank levers 54 being provided regardless of the contours of the particular section joints. These flexible elements, as shown in Figures 3, 8 and 9, project through openings in the casing sections 29 (or 75 or 80) and terminate in manually engageable ends 85, which may be in the form of knobs, arranged in recesses 86 formed in the associated casing sections. The flexible elements 83 may project through openings 87 in the recesses 86 and the latter, as shown in Figure 3, may be provided with sheet metal guides 88 to facilitate the turning of the flexible element around the angles necessary for them to project through the respective openings 87.

From the foregoing it will be apparent that the operating mechanism for each longitudinal and transverse joint is the same with respect to all of the sections except that flexible shafts are employed where necessary to rock the crank fingers 50. It will be apparent that the operating mechanism includes all of the elements shown in Figures 3 and 4, for example the bolts 36, the arrangement of the compressible packing elements 26, etc.

The boat may be made in the form shown in Figures 1 and 2, and the complete boat may be furnished with an alternative stern section 95 as shown in Figure 10. This section may have an upstanding transom board 96 to which an outboard motor can be rigidly connected, and the section 95 will carry one of the compressible packing members 26. The stern section 95 also will house the elements arranged within the left-hand casing section 29 of Figure 4 so that the adjacent boat section 13 may be connected thereto in the same manner as would be true with the use of one of the bow sections 11.

The operation of the apparatus is as follows:

Various half-sections are brought together in proper relationship to the other sections in any desired sequence. Preferably the two halves of each section are first brought together, followed by the assembling of the sections with respect to each other. Referring to Figure 4, the two half-sections represented in such figure are moved into proximity to each other and the end of the bolt 36 is inserted in the socket 48. The parts are moved manually toward each other with the handle 70 (Figure 4) swung downwardly and to the left until the crank finger 50 clears the bolt 36.

As the parts are moved together, the rounded advancing end of the bolt 36 will move the lever arm 53 upwardly against the tension of the spring 61. Because of the packing member 26, the parts cannot be moved to relative positions in which the lever arm 53 will drop into the notch 52, it being necessary to compress or deform the packing member 26 before such operation can take place.

With the parts assembled to the position referred to, the handle 70 is then swung upwardly, rotating in a clockwise direction relative to the shaft 46 as viewed in Figure 4. The crank finger 50 of each latching device of the two half-sections being assembled will engage the square end of the associated notch 51, thus applying force to each bolt 36 to move the two half-sections 14 relatively toward each other.

The operation referred to transmits positive movement from each bolt 36 through its shank 38 to the nut 39, and the latter element transmits resilient force through spring 40 to the head 37. The spring 40 is relatively stiff and is capable of transmitting sufficient force to the right hand half-section 14 in Figure 4 to deform the packing member 26 to the extent necessary to permit the bolt 36 to move to its proper position with the notch 52 in alignment with the lever arm 53. This lever arm will then drop into the notch 52 and the parts will be locked together.

The deforming of the packing element 26 takes place with the tapered edge of such element moving along the tapered top and bottom surfaces of the recess 24. Thus a tight seal is provided to prevent any leakage around the packing member.

Each successive pair of half-sections is assembled in the same manner, whereupon successive pairs of whole sections are brought into proper relationship with each other. The operation of assembling such complete sections is identical with the operation previously described and need not be referred to in detail. Referring to Figure 6, it will be obvious that each complete section is provided with the same projecting bolts 36 receivable in the sockets or cylinders of the adjacent end of the next adjacent boat section. After the complete sections have been moved together as far as possible by hand in the manner pre-

viously described, the handle 70 associated with one of the complete sections (see Figure 6) is then operated to force the sections into the proper cooperative relation for engagement of the lever arm 53 (Figure 8) with the notches 52 (of the bolts 36).

As stated, there is no distinction in the modes of operation involved in bringing the various sections together. The only difference is structural, flexible shafts (76 in Figure 8 and 82 in Figure 9) being employed for rocking the crank fingers 50 where straight rigid shafts cannot be employed. After all of the parts have been assembled, a rigid unitary structure is provided and the boat may be freely used without danger of the disengagement of the parts and without any leakage between the various sections.

When the parts are to be disassembled, the knobs 85 associated with the various flexible elements 83 are pulled to release the lever arms 53 from the notches 52. It will be apparent that due to the pressure of one side of each notch 52 against its associated lever arm 53, there will be very substantial frictional resistance to the disengagement of the lever arms 53.

In disconnecting the parts, therefore, the operator will first move the handle 70 (Figure 3) of the two sections or half-sections to be disengaged, to rotate the associated crank fingers 50 to a slight extent in a clockwise direction as viewed in Figure 4. This action will relieve the pressure against the associated lever arms 53. While holding the handle 70 in the position referred to, the operator can then readily pull the knob 85. This operation will transmit movement through the flexible element 83 to rock the bell crank levers 54 associated therewith (Figure 3) to disengage the lever arms 53. While holding the flexible element 83 in such position, the operator will release the handle 70, whereupon the spring 40 (Figure 4) will move the associated bolt 36 to a position in which the corresponding lever arm 53 will be out of alignment with the notch 52. The knob 85 will then be released, whereupon the two boat sections can be pulled apart. This operation is repeated until the boat is completely disassembled.

It will be apparent that the separated boat sections may be relatively easily stored and nested for transportation. For example, for storage and transportation each half-section 14 may be reversed and nested within the opposite half-section, and this operation may be repeated as to the various sections of the boat to minimize the storage and transportation space required.

Where an outboard motor is to be used with the boat, the stern section 95 shown in Figure 10 will be substituted for one of the bow sections 11. The stern section in Figure 10 corresponds to the bow section shown in Figure 6, having the openings and sockets for the reception of the bolts 36 of the next adjacent boat section.

The pontoons 17 (Figures 1 and 2) are preferably employed to add stability and buoyancy to the boat, particularly when it is used in rough water. These pontoons may be of any desired internal structure to provide the necessary buoyancy and are readily attached to and disconnected from the sides of the boat.

70 I claim:

1. In a boat structure, a pair of separable sections having edges adapted to be brought into contacting relation, a bolt carried by one section and projecting from the edge thereof, a socket carried by the other section to receive said bolt,

a manually operable crank element carried by said other section and engageable with said bolt to move said edges into engagement with each other, and means carried by said other section for engaging said bolt to lock said sections in edge to edge relation.

2. In a boat structure, a pair of separable sections having edges adapted to be brought into contacting relation, a plurality of bolts carried by one of said sections, a plurality of sockets carried by the other section to receive the respective bolts, latch means carried by said other section and engageable with each of said bolts to lock said edges in contacting relation, and common means for operating all of said latch means.

3. In a boat structure, a pair of separable sections having edges adapted to be brought into contacting relation, a plurality of bolts carried by one of said sections, a plurality of sockets carried by the other section to receive the respective bolts, latch means carried by said other section and engageable with each of said bolts to lock said edges in contacting relation, common means for operating all of said latch means, and deformable packing means arranged between said edges and extending from end to end thereof, said packing means being deformed under pressure when said latch means engage said bolts.

4. In a boat structure, a pair of separable sections having edges adapted to be brought into contacting relation, a plurality of bolts carried by one of said sections, a plurality of sockets carried by the other section to receive the respective bolts, latch means carried by said other section and engageable with each of said bolts to lock said edges in contacting relation, common means for operating all of said latch means, deformable packing means arranged between said edges and extending from end to end thereof, and means for moving said edges into contacting relation and for deforming said packing means, said latch means being engageable with said bolts after operation of said last named means to hold said packing means under pressure.

5. In a boat structure, a pair of separable sections having edges adapted to be brought into contacting relation, a plurality of bolts carried by one of said sections, a plurality of sockets carried by the other section to receive the respective bolts, a plurality of levers carried by said other section and each having a lever arm, each bolt having a notch engageable with its associated lever arm, means biasing each lever arm into engagement with its notch, and common means for operating said levers to release said lever arms from said notches.

6. In a boat structure, a pair of separable sections having edges adapted to be brought into contacting relation, a plurality of bolts carried by one of said sections, a plurality of sockets carried by the other section to receive the respective bolts, a plurality of levers carried by said other section and each having a lever arm, each bolt having a notch engageable with its associated lever arm, means biasing said lever arm into engagement with its notch, common means for operating said levers to release said lever arms from said notches, and deformable packing means arranged between said edges and extending throughout the length thereof, said packing means being held under compression when said lever arms are engaged in said notches.

7. In a boat structure, a pair of separable sections having edges adapted to be brought into contacting relation, a plurality of bolts carried by

one of said sections, a plurality of sockets carried by the other section to receive the respective bolts, a plurality of levers carried by said other section and each having a lever arm, each bolt having a notch engageable with its associated lever arm, means biasing each lever arm into engagement with its notch, common means for operating said levers to release said lever arms from said notches, a deformable packing strip arranged between said edges and extending throughout the length thereof, and means engaging each of said bolts to effect movement of said edges into engagement with each other and to deform said packing strip, said lever arms being engageable in said notches when said packing strip is deformed.

8. In a boat structure, a pair of separable sections having edges adapted to be brought into contacting relation, a plurality of bolts carried by one of said sections, a plurality of sockets carried by the other section to receive the respective bolts, latch means carried by said other sections and engageable with each of said bolts to lock said edges in contacting relation, common means for operating all of said latch means, a deformable packing strip arranged between said edges and engageable with both such edges prior to contact therebetween whereby deforming of said packing strip is necessary to bring said edges into contacting relationship, a crank arm engageable with each bolt, and a manually operable shaft carrying said cranks and rotatable to effect movement of said bolts to bring said edges into contact with each other, said lever arms being engageable in said notches only when said edges are brought into contact with each other.

9. In a boat structure, a pair of separable sections having edges adapted to be brought into contacting relationship, a plurality of bolts carried by one of said sections and projecting from its said edge, a plurality of sockets carried by the other section to receive the respective bolts, a plurality of bell crank levers carried by said other section, each bolt having a notch and each lever having a lever arm engageable in one of said notches when said edges are in contacting relation to lock said sections together with said edges in contact with each other, and a flexible element connected to the other arms of said bell crank levers to rock them and disengage said first named arms from said notches.

10. In a boat structure, a pair of separable sections having edges adapted to be brought into contacting relationship, a plurality of bolts carried by one of said sections and projecting from its said edge, a plurality of sockets carried by the other section to receive the respective bolts, a plurality of bell crank levers carried by said other section, each bolt having a notch and each lever having a lever arm engageable in one of said notches when said edges are in contacting relation to lock said sections together with said edges in contact with each other, a flexible element connected to the other arms of said bell crank levers to rock them and disengage said first named arms from said notches, and a deformable packing strip arranged between said edges and extending throughout the length thereof, said packing strip being such that deforming thereof is necessary to bring said edges into contacting relationship.

11. In a boat structure, a pair of separable sections having edges adapted to be brought into contacting relationship, a plurality of bolts carried by one of said sections and projecting from

its said edge, a plurality of sockets carried by the other section to receive the respective bolts, a plurality of bell crank levers carried by said other section, each bolt having a notch and each lever having a lever arm engageable in one of said notches when said edges are in contacting relation to lock said sections together with said edges in contact with each other, a flexible element connected to the other arms of said bell crank levers to rock them and disengage said first named arms from said notches, a deformable packing strip arranged between said edges and extending throughout the length thereof, said packing strip being such that deforming thereof is necessary to bring said edges into contacting relationship, and means for exerting a relative force between said sections to bring said edges into contact with each other and to deform said packing strip.

12. In a boat structure, a pair of separable sections having edges adapted to be brought into contacting relationship, a plurality of bolts carried by one of said sections and projecting from its said edge, a plurality of sockets carried by the other section to receive the respective bolts, a plurality of bell crank levers carried by said other section, each bolt having a notch and each lever having a lever arm engageable in one of said notches when said edges are in contacting relation to lock said sections together with said edges in contact with each other, a flexible element connected to the other arms of said bell crank levers to rock them and disengage said first named arms from said notches, a deformable packing strip arranged between said edges and extending throughout the length thereof, said packing strip being such that deforming thereof is necessary to bring said edges into contacting relationship, a crank finger engageable with each bolt, a shaft carrying said crank fingers, and a handle connected to said shaft and operable for swinging said crank fingers in one direction to effect movement of said bolt and consequently relative movement of said sections to bring said edges into contacting relationship.

13. In a boat structure, a pair of separable sections having edges adapted to be brought into contacting relation, a plurality of bolts carried by one of said sections and projecting from said edge of such section, spring means interposed between each bolt and said one section to tend to oppose movement of each bolt in the direction of its projection, a plurality of sockets carried by the other section to receive the respective bolts, each bolt having a notch therein, and latch means carried by said other section and engageable in said notches to lock said sections with said edges in contacting relation.

14. In a boat structure, a pair of separable sections having edges adapted to be brought into contacting relation, a plurality of bolts carried by one of said sections and projecting from said edge of such section, spring means interposed between each bolt and said one section to tend to oppose movement of each bolt in the direction of its projection, a plurality of sockets carried by the other section to receive the respective bolts, each bolt having a notch therein, latch means carried by said other section and engageable in said notches to lock said sections with said edges in contacting relation, and deformable packing means arranged between said edges and extending from end to end thereof, said packing means

being deformed and said spring means being deflected from normal when said latch means are in engagement with said notches.

15. In a boat structure, a pair of separable sections having edges adapted to be brought into contacting relation, a securing member carried by one section and projecting from the edge thereof, manually operable means carried by the other section and engaging said securing member for effecting clamping engagement of said sections toward each other, and means carried by the other of said sections for engaging the projecting end of said securing member to fix said sections relative to each other.

16. In a boat structure, a pair of separable sections having edges adapted to be brought into contacting relation, a securing member carried by one section and projecting from the edge thereof, manually operable means carried by the other section comprising a crank engaging said securing member for effecting clamping movement of the edges of said sections toward each other, and means separate from said manually operable means for engaging the projecting end of said securing member to lock said sections in edge to edge relation.

17. In a boat structure, a pair of separable sections having edges adapted to be brought into contacting relation, a securing member carried by one section and projecting from the edge thereof, the other of said sections having a socket to receive the projecting end of said securing member, manually operable means connected between said securing member and said other section for effecting clamping movement of said edges of said sections into engagement with each other, and means separate from said manually operable means and carried by said other section for engaging the projecting end of said securing member to lock said sections in edge to edge relation.

18. In a boat structure, a pair of separable sections having edges adapted to be brought into contacting relation, a securing member carried by one section and projecting from the edge thereof, the other of said sections having a socket to receive the projecting end of said securing member, manually operable means connected between said securing member and said other section for effecting clamping movement of said edges of said sections into engagement with each other, the projecting end of said securing member being laterally notched, and means carried by said other section and movable laterally relative to said securing member to engage said notch and lock said sections in edge to edge relation.
